UNITED STATES PATENT OFFICE.

CHARLES M. LUNGRÉN, OF BAYONNE, NEW JERSEY, ASSIGNOR TO THE
SAFETY CAR HEATING & LIGHTING COMPANY, OF NEW YORK, N. Y., A
CORPORATION OF NEW JERSEY.

METHOD OF FORMING AN INCANDESCENT GAS-MANTLE.

No. 845,184.

Specification of Letters Patent.

Patented Feb. 26, 1907.

Application filed August 12, 1904. Serial No. 220,474.

To all whom it may concern:

Be it known that I, CHARLES MARSHALL LUNGRÉN, residing at Bayonne, in the county of Hudson and State of New Jersey, have invented certain new and useful Improvements in Methods of Forming Incandescent Gas-Mantles; of which the following is a full, clear, and exact description, such as will enable others skilled in the art to which it applies to make and use the same.

This invention relates to a method of forming a mantle for use in connection with gas-burners.

The mantle as an article is shown, described, and claimed in my companion application filed of even date herewith and is not claimed herein. It may be stated, however, that said mantle, although it may be burned at any angle, is especially adapted to be suspended from its point of support, it being provided with a thickened free end or crown and a hardened supporting end.

One of the objects of this invention is to provide a method whereby such a mantle may be formed which will be strengthened and reinforced at parts which are subject to the greatest stresses and would otherwise be most likely to break.

Another object is to provide a method whereby an article of the above type may be made with a smooth and uniform surface.

Another object is to provide a method whereby articles of the above nature may be conveniently and efficiently formed in any desired shape.

Other objects will be in part obvious and in part pointed out hereinafter.

This invention accordingly consists in the steps and the order and relation of one or more of the same to each of the others thereof, which will be exemplified in the process herein described and the scope of the application of which will be indicated in the following claims.

In the accompanying drawings, wherein are illustrated several of the steps of this process, showing one of various possible forms of apparatus for carrying on the same, Figure 1 is a sectional elevation of a mantle, together with the spool or other member from which it is supported. Fig. 2 is a similar view showing a slightly different form of mantle. Fig. 3 is a diagrammatic view

showing one of the first steps of the process. Fig. 4 is a diagrammatic plan of the manner in which the end of the mantle may be closed. Fig. 5 shows a method of placing a fastening-string or other securing device about the base of the same. Fig. 6 shows a mantle mounted upon its supporting-spool and distended in accordance with one of the steps of the hereinafter-described process. Fig. 7 is a similar view in which the distending means is collapsed, so as to permit withdrawal thereof.

Similar reference characters refer to similar parts throughout the several views.

Referring now to Fig. 3, 1 represents a mandrel or wood or other desired material upon which is drawn a suitable length of fabric preferably woven in tubular form. Mandrel 1 is provided with a rounded upper end, and the fabric 2 is slipped down slightly below the same and unraveled, so as to expose along its upper edge a series of loops 3, the thread which is unraveled being tied or made fast in any desired manner. Through loops 3 is inserted a thread or gathering-string 4, which may be conveniently done by a needle, as shown in the drawings. The two ends of this thread are then drawn, so as to gather the upper end of fabric 2, leaving a small opening at the end thereof, and the ends of this thread are then tied. This gathering of the end of the fabric is not carried to such an extent as entirely to close the end of the same, as in that case the resulting wrinkles are difficult to remove. Such wrinkles as may be present are now smoothed out by pressing against the form or mandrel 1 over which the fabric is stretched, and the remaining opening above mentioned is darned, substantially as shown in Fig. 4. By means of the darning the fabric immediately surrounding the opening in the crown is thickened to any desired extent and the opening itself closed by any desired thickness of material. It may here be noted that by the word "crown" or "apex" is meant that end of the mantle which is remote from the part upon which the mantle is supported.

With the mantle in the above form a string 5, preferably of asbestos, is passed through the base thereof, as shown in Fig. 5, and drawn tightly, so as to press the fabric into an annular groove 6 in mandrel 1 at that

point. The fabric is then turned up over the asbestos string or cord 5 and sewed in place and the rough edges thereof trimmed off. The hood is then reversed, placing the string 5 with the upturned portion of the mantle upon the inside and leaving a smooth outer surface with a uniform edge at the bottom of the same. If desired, the crown of the hood may then be reinforced by means of additional darning upon the outer surface thereof. The hood is then attached to a spool or other supporting member 7, by means of which it is secured to the burner, the ends of the asbestos string 5 being drawn tightly into the groove 8 upon the spool and then tied. The mantle is now ready for the impregnating solution, which may be of any desired composition.

After impregnation the hood is shaped as follows. A tube 9, having thereon a bag or rubber or similar material 10, is inserted through spool 7 and by means of compressed air or a similar agency is expanded, so as to fill and distend the mantle to any desired extent, depending partly upon the original shape of the hood and partly upon the shape of the distending member. As will readily be seen, this may be easily accomplished, notwithstanding the shape of the mantle and the size of the same with reference to the diameter of the opening through the spool. In this way I am enabled to handle the wet impregnated hood or sac readily and conveniently and give it its desired shape, notwithstanding the character and condition of the material. With the bag or "balloon" in its distended form the mantle is dried. This step may be carried on in the air, if desired; but in order to save time the drying is preferably accelerated by means of inserting the mantle with the balloon distended therein in an oven or similar source of heat. When thoroughly dried, the balloon is removed by releasing the air-pressure therein and allowing the same to shrink, as is shown in Fig. 7 of the drawings, and it may then be withdrawn through the opening in the spool 7. The mantle is at this stage dried and shaped and is in condition for such further steps as may be necessary to prepare it for use. These steps form no part of the present invention and will not be herein described in detail.

In Fig. 2 is shown a tubular form of mantle, as distinguished from the globular or spherical form shown in Figs. 1, 6, and 7. It will be understood that the several steps herein described are substantially identical in the process of forming the different shapes, the form of mandrel, length of fabric, and form of balloon being varied so as to attain the desired result. It will be obvious that where these mantles are to be produced in large quantities the hood may be knit to shape, thus mechanically closing the end of the tubular fabric. Where this is done the rein-

forcement of the end may be provided for at the time the hood is formed or may be accomplished manually, as by the darning step described.

It will thus be seen that I have provided a method whereby a mantle may be formed which possesses a smooth outer surface and is reinforced at such places as are exposed to the greatest stresses in use. It will also be seen that the mantle may be formed and dried in accordance with this process in any desired shape, a single piece of apparatus serving the purpose of distending mantles of various sizes and shapes. The apparatus is simple and inexpensive, and the process may be carried on by means of comparatively unskilled labor, and it will be found to consume a comparatively short space of time.

The advantages of pressing the fabric against the mandrel upon which the end is closed, in that inequalities in the surface thereof may be thus smoothed out and the whole made to conform to the desired shape, will be readily seen in connection with the above description. Also the advantages of applicant's method of inserting the draw-string, whereby the mantle is smoothly stretched or drawn over the mandrel by means of forcing the string into the groove and whereby an inwardly-turned edge, including the draw-string, may be formed about the open end of the mantle, are all of marked value. Other advantages will be obvious from the above description of one mode of practicing my process.

As my process could be carried on with widely-different apparatus or by manipulation in whole or part and is valuable in other relations without departing from the scope of my invention, I intend that all matter contained in the above description or shown in the accompanying drawings shall be interpreted as illustrative and not in a limiting sense.

Having described my invention, what I claim as new, and desire to secure by Letters Patent, is—

1. The method of shaping a mantle which consists in inserting a member therein, causing the same first to increase in size to a diameter greater than that of the open end of the mantle, and then to diminish in size and withdrawing said member.

2. The method of shaping a damp flexible member which consists in inserting a second flexible member, inflating said second flexible member drying said first-mentioned member and deflating and withdrawing the second-mentioned member.

3. The method of shaping a damp mantle which consists in inserting a member therein, causing the same first to increase so as fully to distend said mantle, and then to diminish in size, drying said mantle in distended condition, and withdrawing the same.

4. The method of shaping a mantle which consists in inserting a rubber bag within the same, inflating said rubber bag so as fully to distend said mantle, and deflating and withdrawing the same.

5. The method of forming a mantle which comprises dipping the same in an impregnating solution and drying the same over an expandible member.

10 6. The method of forming a mantle which comprises inserting an expandible member, expanding the same so as to entirely distend said mantle, drying said mantle in its distended form, and deflating and withdrawing 75 said expandible member.

15 7. The method of forming a mantle which comprises stretching a piece of fabric woven in tubular form over a mandrel, drawing together and darning one end of said fabric, and inserting and inflating a flexible member within the said fabric so as to distend the same, drying the same and deflating and withdrawing such flexible member.

20 8. The method of forming a mantle which 25 comprises stretching a piece of fabric over a mandrel, drawing together and darning one end of said fabric, pressing said fabric against said mandrel so as substantially to eliminate inequalities in the surface of said fabric, inserting and inflating a flexible member within the same, drying said fabric, and deflating and withdrawing said flexible member.

25 9. The method of forming a mantle which 30 consists in stretching a piece of fabric over a mandrel, drawing together and darning one end of said fabric to a thickness greater than that of the remainder thereof, pressing said fabric against said mandrel so as substantially to eliminate inequalities in the surface of said 35 fabric, impregnating the resulting mantle, inserting a flexible member within the same, inflating said flexible member so as fully to distend said mantle, drying said mantle with said flexible member in inflated condition, 40 and deflating and withdrawing said flexible member.

45 10. The method of forming a mantle which 50 comprises stretching a piece of fabric over a mandrel, drawing together and darning one end of said fabric, placing a string about said fabric adjacent the other end, forcing said fabric into a groove in said mandrel by means of said string, turning the free end of said fabric against the remainder thereof and making the same fast thereto, inserting a flexible member and inflating the same within the resulting mantle, and deflating and withdrawing said flexible member.

55 11. The method of forming a mantle which 60 comprises stretching a piece of fabric woven in tubular form over a mandrel, drawing together and darning one end of said fabric to a thickness greater than that of the remainder thereof, pressing the resulting mantle against 65 said mandrel so as substantially to eliminate

inequalities in the surface of said mantle, placing a string about said mantle adjacent the upper end thereof, turning the free end of said mantle over said string and against the remainder thereof and making the same fast thereto, reversing said mantle, inserting an expandible member within the same, inflating said expandible member so as fully to distend said mantle, drying said mantle and deflating and withdrawing said expandible member.

70 12. The method of forming a mantle which comprises exposing the same to the action of an impregnating solution, inserting an expandible member, expanding the same so as to entirely distend said member, drying said mantle in its extended form, and deflating and withdrawing said expandible member.

75 13. The method of forming a mantle which 80 consists in stretching a piece of fabric woven in tubular form over a mandrel, drawing together and darning one end of said fabric, exposing the resulting mantle to the action of an impregnating solution, inserting and inflating a flexible member within said mantle so as 85 to distend the same, drying the same, and deflating and withdrawing said flexible member.

80 14. The method of forming a mantle which 85 consists of stretching a piece of fabric over a mandrel, drawing together and darning one 90 end of said fabric, placing a string about said fabric adjacent the other end, forcing said fabric into a groove in said mandrel by means of said string, turning the free end of said fabric against the remainder thereof and making the same fast thereto, exposing the resulting mantle to the action of an impregnating solution, inserting and inflating a flexible member, drying said mantle, and deflating and withdrawing said flexible member.

90 15. The method of forming a mantle, 95 which consists in stretching it over a mandrel, reinforcing one end thereof so as to make it thicker than the body of the remainder, pressing said mantle against said mandrel so as to substantially eliminate inequalities in the surface of said mantle, impregnating said mantle and inserting a flexible member within the same, inflating said flexible member so as to fully distend said mantle, drying said 100 mantle with said flexible member in inflated condition, and deflating and removing said flexible member.

100 16. The method of forming a mantle, 105 which comprises placing the mantle upon a mandrel forming one end of greater thickness than that of the remainder thereof, pressing the same against said mandrel so as to substantially eliminate inequalities in the surface of said mantle, placing a string about 110 said mantle adjacent one end thereof, turning the free end of said mantle over said string against the remainder thereof and making the same fast thereto, reversing said mantle, inserting an expandible member within the 115

same, inflating said expansible member so as to fully to distend said mantle, drying said mantle and deflating and withdrawing said expansible member.

17. The method of forming a mantle, which consists in placing said mantle upon a mandrel forming one end of the same of a thickness greater than that of the remainder thereof, forcing said mantle into a groove in said mandrel by means of said string, turning the free end of said mantle against the remainder thereof and making the same fast thereto, exposing said mantle to the action of an impregnating solution, inserting and inflating a flexible member, drying said mantle and deflating and withdrawing said flexible member.

18. The method of forming a mantle which comprises dipping the same in a solution, inserting an expansible member therein, while the same is in a moist condition, expanding the same so as to distend said mantle, drying said mantle and contracting and removing said expansible member.

19. The method of forming a mantle which comprises dipping the same in a solution, inserting within the same an inflatable member while said mantle is in moist condition, inflating said inflatable member, drying said

mantle, and deflating and removing said inflatable member.

20. The method of forming a mantle which comprises inserting an expansible member within the means which is to form the mantle, expanding the same, drying said means upon said expansible member, contracting and withdrawing said expansible member, and burning said mantle-forming means.

21. The method of shaping a mantle which comprises inserting an inflatable member within the means which is to form the mantle, inflating the same, drying said means about said inflated member, deflating and withdrawing said inflatable member.

22. The method of shaping a mantle which comprises inserting an inflatable member within the means which is to form the mantle, inflating the same, drying said means about said inflated member, deflating and withdrawing said inflatable member; and burning said means.

In testimony whereof I affix my signature in the presence of two witnesses.

CHARLES M. LUNGRÉN.
